UNITED STATES PATENT OFFICE

2,602,720

HAIRPIN DISPENSER

Betty Steinberg, Beverly Hills, Calif.

Application April 11, 1949, Serial No. 86,785

15 Claims. (Cl. 312—92)

1

The present invention relates to an improved dispenser for hair pins, bobby pins, paper clips and the like, and has particular applicability to dispensing hair pins and bobby pins.

It is desirable that hair pins, bobby pins and the like be maintained in a predetermined position, being a readily accessible one, and of such nature that there is little likelihood that the appearance of a woman's dressing table might be impaired in day to day use of such articles, and such that the necessity of searching for such "lost" pins is greatly reduced.

The dispenser as shown and claimed herein is generally of the type shown and claimed in my co-pending patent application, Serial No. 41,930, filed August 2, 1948, now Patent No. 2,544,114, issued March 6, 1951, and incorporates small magnets which are arranged to dispense hair pins, bobby pins and the like from a pile in which they are randomly disposed. In accordance with the present dispenser, however, it is not necessary that the hair pins be of special magnetic construction, and, in fact, one of the important features of the present invention is that conventional present day hair pins and bobby pins may be dispensed from my improved dispenser.

It is therefore an object of the present invention to provide an improved arrangement whereby the aforesaid desirable results may be obtained.

Another object of the present invention is to provide a dispenser of this character which incorporates magnetic means for dispensing hairpins but which does not require for its operation specially magnetized or fabricated hairpins or bobby pins, the dispenser being effective to dispense hair pins, bobby pins and the like of standard wire construction.

Still another object of the present invention is to provide an improved dispenser arranged to dispense, in orderly fashion, hair pins, bobby pins and the like disposed in random fashion.

The features of the present invention which are believed to be novel are set forth with particularity in the appended claims. This invention itself, both as to its organization and manner of operation, together with further objects and advantages thereof, may be best understood by reference to the following description taken in connection with the accompanying drawings in which:

Figure 1 is a perspective view of a hair pin dispenser embodying features of the present invention, and shows the relation of the parts of the dispenser when and as the attracted hair pins

2

are being moved out of their individual compartments to a raised position,

Figure 2 is a sectional view taken substantially on the line 2—2 of Figure 1.

Figure 3 is a view similar to Figure 2 but with the hair pin extractor moved to its uppermost position,

Figure 4 is a view similar to Figure 2, but shows the hair pin extractor element moved to its lowermost position from its uppermost position shown in Figure 3, and

Figure 5 is a sectional view taken substantially on the line 5—5 of Figure 2.

The hairpin dispenser shown in the drawings 15 functions to dispense hairpins 10, one by one, from corresponding compartments 11 in which they are randomly disposed in a generally vertical position with the U-bend in such hairpins up, upon repeated reciprocal up and down movement 20 of the hairpin extractor and stripping element 12.

The dispenser is mounted on the base 14 adapted to rest upon a flat surface such as a table or dresser top. The base 14 has affixed thereto a pair of generally vertically extending legs or 25 standards 15, 16, each of which has mounted thereon a pair of oppositely disposed generally U-shaped tracks 17, 18 respectively, within which the corresponding vertically disposed metal strips 19, 20 of the element 12 move and are guided in the up and down movement of such element 12.

These strips 19, 20 are affixed at their upper ends to the crossbar 22 of the element 12, and have the handle member 23 thereon for convenient manual grasping and moving up and down.

The crossbar 22, of non-magnetic material such as Bakelite or the like, has imbedded therein a plurality of cylindrical Alnico magnets 25, the lower ends of which project below the crossbar 22 within which they are imbedded. These magnets 25 are adapted to register with the corresponding hairpin openings 26, and to be immediately above and to contact the relatively stationary plastic plate 29 within which such apertures 26 are formed when the element 12 is in its lowermost position. In other words, the stationary plate 29 is affixed to the upstanding standards 15, 16 and serves as a stop member to limit downward movement of the reciprocal element 12. Upward movement of such element 12 may be limited, using any one of different expedients, and is, for example, limited by laterally extending pins 27 on the plate 29 engaging a portion of the track 18 at the upward end of travel of the element 12. In other words, the pin 27 extends through a slot 30 in the guide member 18, and at

the upper end of travel of the element 12 the pin 27 is at its uppermost position in such slot 30, to thereby restrain further upward movement of the element 12.

The pins 27, one of which is on both the plate 19 and plate 20, serve an additional important function, namely, to serve as a pivot for the spring biased hair pin stripper element 34, which is pivotally mounted on the pins 27, and which is normally biased inwardly in the plane of the drawing sheet in Figure 1 by small torque springs 35. These springs 35 are affixed at a point intermediate their respective ends to the crossbar 22, and have their stressed free ends in engagement with the hair pin stripper element 34 to thereby tend to normally bias the element 34 against the magnets 25. Stripper element 34 is a generally inverted U-shaped element with its vertically disposed legs pivoted on the pins 27, and has the upturned flange 34A adapted to contact the magnets 25 to thereby serve as a stop member for pivotal movement of the element 34.

It is noted that this stripper element 34 is thus mounted on the legs 19, 20 and is thus movable with the element 12.

Although the stripper element 34 moves up and down with the element 12, it is automatically moved laterally with respect to the magnets 25 thereon, to automatically strip the hair pins 10 from the magnets 25 when and as the element 12 assumes its uppermost vertical position.

In other words, in the lowermost position of the element 12 (shown in Figure 4) the stripper element 34 is displaced laterally with respect to the magnet 25 to allow such magnet 25 to engage an attracted hair pin 10; but, in the uppermost position of the element 12, represented approximately in Figure 3, the stripper element 34 is moved laterally with respect to the magnet 25 to cause the hair pin 10 to be displaced to the left out of the path of subsequent downward movement of the magnet 25.

This automatic movement of the stripper element 34 from a relative position shown in Figure 4 to a relative position shown in Figure 3 is provided by a cam action. This cam action is perhaps best illustrated in Figure 2, and is produced by engagement of the legs of the stripper element 34 with a projection 42 (Figure 5) of the stationary plate 29. It is noted that the stripper element 34 is normally pressed into engagement with such projection 42 by the torque springs 35 (Figure 1) and the legs of the stripper element 34 are so shaped with respect to the abutment 42 that the above mentioned desirable movement of the stripper element 34 is automatically obtained when and as the element 12 is reciprocated up and down.

The stationary plate 29 serves also as a closure member for the compartmented pivoted tray 50. This tray 50 is movable from the full line position shown in Figure 2 to the dotted line position shown in the same figure about the shaft 51, which has its opposite ends affixed to the standards 15, 16. This compartmented pivoted tray 50 with the individual compartments 11 therein is preferably made of plastic to allow vision of the number of hair pins remaining in such compartments 11. In order to replenish the supply of hair pins in such compartments 11, the unit 50, as a whole, is pulled outwardly to its dotted line position shown in Figure 2 by grasping and pulling the attached handle 52 outwardly. Suitable stop means may be provided for limiting such outward movement of the tray 50 to its position

shown in Figure 2, wherein it is in a position of stable equilibrium. Such stop means may, for example, comprise a pin 60 attached to and extending inwardly from the standard 15 into an arcuate motion limiting slot 61 in the side wall of the movable tray 50.

In its inward position in Figure 2 the tray 50 is also in a position of stable equilibrium abutting against the inclined stationary plastic wall 64 mounted on the standards 15, 16 by gluing or by mechanical fastening elements.

It is noted that the stationary plate 29 has its plane mounted substantially perpendicular to the plane of the back plate 64, and is thus inclined downwardly and rearwardly for an important purpose, to thereby provide an inclined shelf 26A immediately behind the apertures 26 upon which the pronged ends of the hair pins may rest, it being noted that originally all of the hair pins, which are of standard construction, are disposed in the compartments 11 with their U-shaped bends upwardly for attraction by the magnets 25. Such rearwardly inclined shelves 26A immediately behind the apertures 26 have raised abutments 26B formed between such adjacent shelf portions to restrict movement of the pronged ends of the hair pins engaging the shelf portions 26A.

Preferably, the front side of the inclined back plate 64, adapted to engage the legs of the hair pin, is suitably roughened, as for example, by scoring to thereby increase the frictional resistance between a hair pin and the inner surface of the plate 64 which such hair pin contacts.

In operation of the device described, originally hair pins are vertically disposed in the compartments 11 with the U-bends of such hair pins uppermost, the hinged tray 50 being moved to its dotted line position shown in Figure 2 to effect such charging of the device. Thereafter, the tray 50 is moved to its full line position from where hair pins are dispensed one by one through the slots 26 in the stationary plate 29, which, incidentally, serves as a cover member for the open mouth of the tray 50. The hair pins 20 are dispensed from such apertures 26 one by one by reciprocating the hair pin dispensing element 12.

In the loading of the device, as described immediately above, the element 12 is preferably in its uppermost position. Then the element 12 is moved downwardly to a position wherein the magnets 25 are effective to attract a hair pin and to pull the same upwardly through the slot 26, which is so shaped to allow the passage of but one hair pin. Thus, in the lowermost position of the element 12, a hair pin clings to each one of the magnets 25. Thereafter, the element 12 is raised, carrying upwardly therewith the hair pins clinging to the magnets 25, as shown in Figure 1.

As the element 12 is moved further upwardly in the direction indicated by the arrow 66 in Figure 1, and further upwardly in the direction indicated by the arrow 67 in Figure 2, the spring biased stripper element 34 is gradually allowed to move to the left in Figure 2, under the influence of the torque spring 35 (Figure 1) to later assume the position shown in Figure 3, wherein it is effective to displace a hair pin in the direction indicated by the arrow 68 in Figure 3 to a position wherein such displaced hair pin is out of the path of movement of the magnet 25 when subsequently such magnet 25 is again moved downwardly. When such hairpin 10 is being displaced to its position shown in Figure 3, the prongs at the lower end thereof are also, of course, displaced

and are positioned above the rearwardly and downwardly inclined shelf portions 26A adjacent to the slots 26.

When and as the magnet 25 thus descends from its uppermost position, the upper end of the hair pin 10 contacts the cylindrical side of the magnet 25 to hold the upper end of the displaced pin in position, but, of course, the bottom end of the pin 10 is prevented from moving downwardly due to its engagement with the shelf 26A, with the net result that when and as the magnet 25 is being moved downwardly the displaced pin 10 remains relatively stationary. Consequently, when the element 12 is in its lowermost position, as shown in Figure 4, the upper end of the displaced pin 10 is in convenient position for manual removal from the device.

After all of such displaced pins 10 are removed, the element 12 is again moved upwardly and then downwardly to again provide conveniently accessible hair pins 10 in the same position as the displaced hair pin 10 shown in Figure 4.

While the device is described specifically in connection with hair pins, it is apparent that likewise the device may be used to dispense other types of pins such as bobby pins, in which case the shape of the slots 26 is altered to assure single file feeding of the bobby pins therethrough, and similarly other clearances are suitably altered, all in accordance with one skilled in the art using the teachings provided herein.

It is noted that the back plate 64 extends upwardly and rearwardly with respect to the base 14, and that the magnetic structure, i. e., the element 12, is movable in a path substantially parallel to the front face of the back plate 64, with the spacing between such magnetic structure or element 12, on the one hand, and such front face of the back plate 64, on the other hand, being substantially equal and slightly greater than the effective "thickness" of the pin 10 whereby such pin, as shown in Figure 4, is confined therebetween.

It is noted further that after a pin 10 is shifted laterally from under the magnetic structure 12, as indicated in Figure 3, the magnet 25 is yet effective to attract and to hold the upper end of the shifted pin 10, to thereby maintain such upper end of the pin 10 in a predetermined position. Simultaneously, the lower end of the shifted pin 10 is moved rearwardly to a position above the shelf portions 26A to bear thereagainst when and as the magnetic structure 12 is moved to its lowermost position, during which the associated magnet 25 exerts an orienting effect on the dispensed pin 10.

Preferably, the front face of the back plate 64 is tilted, as shown in the drawings, because the lower pronged ends of the shifted pin is more inclined to be positioned above the shelf members 26A; this is due to the action of gravity forces on the pin.

While the particular embodiments of the present invention have been shown and described, it will be obvious to those skilled in the art that changes and modifications may be made without departing from this invention in its broader aspects and, therefore, the aim in the appended claims is to cover all such changes and modifications as fall within the true spirit and scope of this invention.

I claim:

1. A hairpin dispenser of the character described comprising: a compartment within which magnetizable hairpins are placed, said compartment having an apertured portion through which

said hairpins may be passed upwardly in single file only, a magnetic structure movable in a predetermined path to a position adjacent and above said apertured portion to permeate said apertured portion with magnetism, said apertured portion having a cross section area slightly larger than the effective cross sectional area of one of said hairpins through which said hairpins may be withdrawn, and means operated in accordance with movement of said magnetic structure for removing the hairpins therefrom, last said mentioned means comprising means pivotally mounted on said magnetic structure and automatically moved transversely of the longitudinal axis of said hairpin near the upper end of magnetic structure movement.

2. A hairpin dispenser of the character described comprising: a compartment for the storage of magnetizable hairpins, an aperture in the upper end of said compartment through which said hairpins are adapted to pass one at a time only, a magnetic structure movable from an elevated position to a lowered position adjacent said aperture to permeate said aperture with magnetism and to attract and to lift upwardly through said aperture said magnetizable objects, said aperture having a cross sectional area slightly larger than the effective cross sectional area of one of said hairpins, a stripping bar pivotally mounted on said magnetic structure and movable therewith in a direction transverse to the longitudinal axis of a hairpin which is attracted to said magnetic structure, said stripping bar being associated with means for automatically moving said stripping bar with respect to said magnetic structure at said elevated position to strip the hairpins attracted by said magnetic structure to allow said magnetic structure to again descend to its lowered position.

3. A hairpin dispenser of the character described having a compartment for the storage of magnetizable hairpins, an aperture in the upper end of said compartment through which said hairpins are adapted to pass, one at a time only, a magnetic structure movable from an elevated position to a lowered position adjacent said aperture to permeate said aperture with magnetism and to attract and to lift a hairpin through said aperture, said aperture having a cross sectional area slightly larger than the effective cross sectional area of one of said hairpins, and means pivotally mounted on said magnetic structure automatically operated in a direction transverse to the longitudinal axis of a hairpin attracted by said magnetic structure to strip an object from said magnetic structure when it is in its uppermost position to allow said magnetic structure to again descend to its lowered position to again lift one of said objects.

4. A dispenser of the character described comprising: a base adapted to rest on a flat horizontal surface, a pair of upstanding standards extending upwardly from said base, a pivoted compartmented tray or bin pivotally mounted with respect to said base and tiltable inwardly and outwardly with respect to said upstanding standards, an apertured cover plate mounted with respect to said standards with its plate extending generally downwardly and rearwardly with respect to the supporting plate of said base, said cover plate forming a cover for said tiltable bin structure when it is in its innermost position, a magnetic structure guided for generally vertical movement on said standards, said base having mounted thereon a back plate, the front sur-

face of which back plate extends generally upwardly and rearwardly with respect to said base, the path of movement of said magnetic structure being generally parallel to said front surface, said cover plate having a shelf portion thereon between an apertured portion and said backplate, a pivotally mounted stripper bar pivotally mounted on said magnetic structure and automatically moved to strip magnetized objects from said magnetic structure when it is near its uppermost position, said magnetic structure being movable to its lowered position wherein it is in proximity to said apertured portions to attract and to lift magnetizable objects originally placed in said bin structure one at a time, through said apertured portions.

5. A dispenser of the character described comprising: a receptacle for vertically disposed magnetizable objects, a base supporting said receptacle, a back plate mounted on said base with its front plane extending generally upwardly and rearwardly with respect to said base, a magnetic structure movable generally parallel with said front plane, said magnetic structure being movable to a lowered position adjacent an aperture in said receptacle to attract and to lift a magnetized object up from said receptacle and through said aperture to an elevated position upon subsequent movement of said magnetic structure, a shelf disposed between said aperture and said front plane, and means operated automatically when said magnetic structure is near its uppermost position for displacing a lifted magnetized object laterally and rearwardly of said magnetic structure to a position wherein the lower end of said magnetized object is above said shelf and the uppermost end of said lifted object is out of the path of movement of said magnetic structure to allow subsequent downward movement of said magnetic structure.

6. A hairpin dispenser of the character described comprising: a base member, a tiltable compartmented bin structure tiltably mounted on said base, the back wall of said bin structure against which magnetizable hairpins rest due to gravity forces thereon being aligned with and cooperating with a stationary apertured cover member through which objects originally placed in said bin structure may pass one at a time, and a magnetic structure movable in a guided path to and from the apertures in said cover member to permeate said apertured portion of the cover member with magnetism, said apertured portion having a cross sectional area slightly larger than the effective cross sectional area of one of said hairpins.

7. In a hairpin dispenser of the character described, a base with a compartment therein into which magnetizable hairpins may be stored, said compartment being at least partially enclosed by an apertured cover member, a magnetic structure relatively movable to a position adjacent the aperture in said cover member to permeate said aperture with magnetism to attract and to lift upwardly through said aperture one of the magnetizable hairpins originally stored therein, said aperture having a cross sectional area slightly larger than the effective cross sectional area of one of said hairpins to allow only one hairpin at a time to pass therethrough, and means pivotally mounted on said magnetic structure effective when said magnetic structure is moved to an uppermost position to shift the lifted magnetizable hairpin therefrom and to allow said magnetic means to again descend to a position adja-

cent said aperture, said compartment being tiltably mounted on said base, with a wall of said compartment against which magnetizable hairpins rest due to gravity forces thereon, being aligned with the apertured portion in said cover member.

8. In a dispenser of the character described, a base having a rear plate mounted thereon with the front face of said plate extending generally upwardly and rearwardly, a magnetic structure spaced from said front face and movable generally parallel to said front face, a receptacle adapted to store magnetizable objects, said receptacle having a top cover member with an aperture therein to assure feeding in single file of magnetizable objects therethrough, said cover member defining a shelf disposed between said aperture and said back plate, said magnetic structure being movable to a position adjacent said aperture to attract and to lift through said aperture a magnetizable object to an elevated position, and means automatically operated when said magnetic structure is moved to a position near its uppermost position for shifting the upper end of said magnetizable object to a position between said front face and said magnetic structure out of the path of subsequent downward movement of said magnetic structure.

9. The invention defined in claim 8, characterized by the fact that said space between said front face and said magnetic structure is comparable to the effective thickness of said article whereby said article is retained therebetween as the magnetic structure descends.

10. In a dispenser of the character described, a receptacle for magnetizable objects having an upper cover element with an aperture therethrough, a back plate extending upwardly and rearwardly with respect to the base of said device, a shelf member disposed between said aperture and said back plate, a magnetic structure movable generally vertically and substantially parallel with the plane of the front face of said back plate, the distance of separation of said magnetic structure and said front face being substantially equal and slightly greater than the effective thickness of said magnetizable object, said magnetic structure incorporating a magnet depending downwardly therefrom and movable to a position adjacent said aperture to attract and to lift through said aperture a magnetized object, means automatically effective when said magnetic structure is near its uppermost position for shifting the lifted magnetized object laterally from said magnet and out of the path of movement thereof into said space between said magnetic structure and said front face, said shelf member being disposed forwardly of a vertical plane passing through the upper end of said magnetizable object after it is shifted laterally from said magnet whereby gravity forces acting on said shifted object tend to position the lower end of said object above said shelf member and adjacent said front face of said back plate.

11. The arrangement set forth in claim 1 in which said apertured portion has contiguous therewith a ledge engaging the lower end of the hairpin after it is withdrawn through said apertured portion.

12. The arrangement set forth in claim 2 in which said aperture has contiguous therewith a ledge engaging the lower end of the hairpin after it is withdrawn through said aperture.

13. The arrangement set forth in claim 3 in

which said aperture has contiguous therewith a ledge engaging the lower end of the hairpin after it is withdrawn through said aperture.

14. The arrangement set forth in claim 6 in which said apertured portion has contiguous therewith a ledge engaging the lower end of the hairpin after it is withdrawn through said apertured portion.

15. The arrangement set forth in claim 7 in which said aperture has contiguous therewith a

ledge engaging the lower end of the hairpin after it is withdrawn through said aperture.

BETTY STEINBERG.
